UNITED STATES PATENT OFFICE.

MELVILLE R. BISSELL, OF GRAND RAPIDS, MICHIGAN.

CARPET-SWEEPER.

SPECIFICATION forming part of Letters Patent No. 329,257, dated October 27, 1885.

Application filed May 9, 1884. Serial No. 130,915. (Model.)

To all whom it may concern:

Be it known that I, MELVILLE R. BISSELL, a citizen of the United States, residing at Grand Rapids, in the county of Kent and State of Michigan, have invented new and useful Improvements in Carpet-Sweepers, of which the following is a specification.

The first part of this invention relates to improvements in the carpet-sweeper for which application for Letters Patent was filed on the 18th day of February, 1884, by W. J. Drew, assignor to the Bissell Carpet Sweeper Company, and has for its objects to simplify the mounting or support of the friction-driven wheel, whereby it is constantly pressed into direct frictional contact with the friction drive-wheel; to provide more simple means for automatically throwing the propelling-handle upright or upward when released by the hands, and to provide more simple means for balancing the weight of the sweeper case or frame on the drive-wheels when the handle is lowered to manipulate the sweeper.

The second part of the invention relates to improvements in the construction of a carpet-sweeper, and has for its objects to provide novel and efficient means to prevent the escape of dust from under the sweeper when operating on a tile or bare floor, and cushioning the sweeper to avoid undue noise in sweeping a tile or bare floor, and to provide novel and simple mechanism for bodily raising or lowering the sweeper case or frame to adjust the position of the brush relative to the floor.

The objects of my invention I accomplish in the manner and by the means hereinafter described and claimed, reference being had to the accompanying drawings, in which—

Figure 1 is a perspective view of a carpet-sweeper embodying my invention, the propelling-handle being lowered as when in use; Fig. 2, an end elevation showing the propelling-handle lowered in full lines and elevated in dotted lines; Fig. 3, an end elevation showing a modified means for placing the driving-belt under tension; Fig. 4, a bottom plan view of the sweeper-bottom, and Fig. 5 a transverse central sectional view of the sweeper.

The sweeper case or frame 1 may be of any usual construction, except in the particulars hereinafter described and claimed, as may

also be the revolving brush-shaft 2 and the dust pan or pans 3. To the side of the case are rigidly attached two brackets, 4, having perforations in their outer ends, through which 55 passes a shaft, 5, the ends whereof project beyond the brackets to receive the loosely-revolving friction drive-wheels 6 6, which are respectively in direct contact with the friction-driven wheels 7 7, arranged on an axle, 9, having a grooved pulley, 10. The ends of the axle are journaled to rotate in bearings 11 at the outer ends of curved spring-plates 12, the other ends of the plates being securely attached to the sweeper-case. As here shown, 60 these plates curve uniformly downward, outward, and upward to form an approximately-semicircular shape, and the inherent elasticity of the plates is such that the driven wheels are constantly pressed upon the drive-wheels 65 to insure the proper rotation of the driven wheels to revolve the brush-shaft by a belt-connection, 13, between the pulley 10 and the brush-shaft. The driving-belt in Figs. 1 and 2 is held under tension or tightened to secure 70 the requisite power to revolve the brush-shaft by a grooved wheel, 14, having an axle, the ends of which are loosely mounted in bearings 15 at the outer ends of two uniformly-curved arms, 16, secured at their other 75 ends to the sweeper-case. The tendency of the spring-arms is to press the wheel downward upon the driving-belt, thereby maintaining the same under proper tension. To increase the frictional contact between the 80 drive and driven wheels, the former or the latter, or all, may be provided with soft-rubber tires. The driving-wheels are, as shown, about twice the diameter of the driven wheels, whereby the latter are rapidly driven by com- 85 paratively slow revolutions of the driving-wheels, thus imparting considerable speed to the brush-shaft by a slow-traveling movement of the sweeper on the floor. The propelling-handle 17 is attached to a bail, the arms 18 of 90 which have eyes 19 at their ends, loosely mounted on the shaft 5, adjacent to the brackets 4. To each arm of the bail is secured one end of a spring, 20, the other end of which is connected with the sweeper-case or some fixed 95 part thereof, the tendency of the springs being to maintain the propelling-handle in an 100

upright position, as in Fig. 2. If the handle be depressed, the tension of the springs is increased, and the weight of the sweeper-case thereby nicely balanced on the driving-wheels, causing the sweeper to run light and easy, which is very desirable, while as soon as the handle is released the tension of the springs restores it to its upright or vertical position. The bottom walls of the dust-pans 3 are each provided with a longitudinal groove, 22, containing a strip of rubber or other flexible material held in the groove by a cleat or longitudinal strip, 23, in such manner that each free edge 24 of the flexible strip projects outward from the bottom wall of the dust-pan, thus constituting a duplex guard or protector to each pan, which prevents the escape of dust from beneath the sweeper when operating on tile or bare floors, while such duplex guard also subserves the function of cushioning the sweeper from such tile or bare floor. I have shown two dust-pans, but a single dust-pan can in some instances be used; but a duplex flexible guard of the character described will be arranged along the edge or near the edge of the opening through which the brush operates. The inside of the front wall of the sweeper-case, at or near the center thereof, is provided with a recess, 25, in which is arranged a wheel, 26, journaled in the forked end 27 of a stem, 28, passing upwardly through an opening in a bracket or support, 29, secured to the sweeper-case. In the top wall of the sweeper-case is a screw-threaded opening, 30, containing a tubular screw, 31, into which the upper end of the stem 28 projects to bear against the head of the screw, or a plug arranged in said screw. By turning the screw in one direction the sweeper case or frame is caused to rise or be adjusted away from the floor, while if the screw be turned in the opposite direction the case will be lowered or adjusted toward the floor. This provides simple and efficient means whereby the position of the brush relative to the floor can be conveniently changed, as occasion may demand, besides which the wheel affords a rolling bearing for the sweeper-case.

I do not confine myself to the particular curve of the spring-plates carrying the driven wheels, nor to any specific number of driving and driven wheels, nor to any particular ar-

angement of the driving mechanism on the sweeper case. If the driving mechanism be arranged centrally on the rear side of the 55 sweeper-case, the latter will be provided with suitable openings for the passage of the endless driving-belt.

In Fig. 3 I show a different means for holding the driving-belt tight or under tension, to 60 secure the requisite power to revolve the brush-shaft, such means consisting of a spiral or other spring, 32, interposed between and connecting the ends of the band composing the driving-belt. 65

Having thus described my invention, what I claim is—

1. The combination, with the case or frame and the brush-shaft, of the friction drive-wheels, the curved spring-plates carried at 70 their inner ends by the case, the axle journaled in the outer ends of the spring-plates and provided with friction-driven wheels held in direct contact with the drive-wheels, and a belt-connection between the axle of the driven 75 wheels and the brush-shaft, substantially as described.

2. The combination of the sweeper-case, the friction drive-wheels, the axle for said wheels carried by the case, the propelling-handle 80 loosely hung on the axle, and the springs connected at one end with the case and at the other end with the handle, and acting to throw the handle to an upright position and to balance the sweeper-case when the handle is depressed, substantially as described. 85

3. The combination, with the sweeper case and the revolving brush-shaft journaled therein, of the dust-pans arranged in front and rear of the brush-shaft, and each having its bottom 90 wall provided with a flexible duplex dust-guard, substantially as described.

4. The combination, with the sweeper-case and the revolving brush-shaft, of the dust-pan having its bottom wall longitudinally grooved 95 and the duplex flexible dust-guard secured in said groove, substantially as described.

In testimony whereof I have hereunto set my hand in the presence of two subscribing witnesses.

MELVILLE R. BISSELL.
